Donee Bain & Ream
Atty.5:

UNITED STATES PATENT OFFICE.

CHARLES W. MCKIBBEN, OF HOUSTON, TEXAS.

METHOD OF OPERATION FOR THE SEPARATION OF LIQUIDS.

1,296,988.

Specification of Letters Patent. Patented Mar. 11, 1919.

Application filed August 17, 1918. Serial No. 250,346.

To all whom it may concern:

Be it known that I, CHARLES W. MCKIBBEN, a citizen of the United States, residing at Houston, in the county of Harris and State of Texas, have invented certain new and useful Improvements in Methods of Operation for the Separation of Liquids, of which the following is a specification.

One of the objects of my invention is to provide a method of operation for the separation of liquids in which one liquid is held or bound in another liquid in a state of tension, as in emulsions of oil and water, whereby a series of separating devices may suitably be connected together in an electric circuit to greatly augment the process of separation and to increase the capacity of the plant without requiring close supervision of the electrical apparatus employed for supplying the current for the purpose.

Another object of my invention is the provision of suitable apparatus whereby my method of separation may be efficiently carried into effect.

In the Patent No. 987,117 to Cottrell *et al.*, there is disclosed a separating apparatus substantially such as illustrated and described herein, with the exception that the source of electric supply is constant potential in character with variable current. In this disclosure, the arrangement of the circuit, in connection with the separating device, is such, that when the globules of water that are held captive in the body of the oil, arrange themselves in nascent chains or streams between the electrodes, paths of relatively low resistance are thus established between the electrodes thereby causing great increase in the value of the current and substantially short-circuiting the electrical apparatus, causing the circuit breaker to open, thus requiring constant expensive supervision.

To prevent formation of chains, Cottrell rotates one of the electrodes so as to break up the chains and prevent their formation. From a series of experiments applicant has found that the separation is effected perfectly when the electrical field is produced by current that may be restricted in value, or prevented from increasing to such an extent as to become discontinued at any time.

Under such circumstances, mechanical agitation of the liquid is not essential, although it may be employed without materially varying the effect produced. The

only object of agitating the liquid is to prevent the formation of chains of polarized globules and the consequent rise of current value to an uncontrollable degree.

As a matter of convenience I have illustrated and described the apparatus shown in the aforesaid Cottrell patent, wherein:

Figure 1 is a vertical sectional view of the apparatus showing my method of connecting the same to the electric circuit and the controller for the current used therein.

Fig. 2 is a cross section taken on line 2—2 of Fig. 1.

Fig. 3 is a diagrammatic illustration of a series of treaters, or separators, connected together and to the current regulating device.

In all the views the same reference characters are employed to indicate similar parts.

1 is an outer shell having a funnel shaped hopper to which the emulsion to be treated is delivered by the pipe 2. Suspended from, and within the shell 1, is a stationary outer electrode 3 which, though it may be of any suitable structure and character, is here shown as a conical annular series of wires. Within the fixed outer electrode 3 and separated therefrom is a rotating inner electrode 4 which may also be of any suitable structural character, being here shown as a conical annular series of wires. In carrying my invention into effect, it is unnecessary that the series of electrodes should be rotated or movable at all. The movement of the liquid passing through the separator when moving with suitable rapidity serves to break up or prevent formation of the chains of globules, the high potential effect of the current and the moving liquid cooperating to overcome the surface tension of the oil envelops or filaments inclosing the water globules.

In the particular embodiment, the inner electrode 4 is carried on a shaft 5, which is itself mounted in a spider 6, which latter is supported on insulator 7 on the top of the hopper of the shell 1. When it is desirable to rotate the inner electrode, rotary motion may be imparted to the shaft 5 in the proper manner, as for example by means of the pulley 8 and the belt 9.

10 is an outlet near the bottom of the shell 1 but raised above the floor thereof, 110 slightly, so that the separated water, indicated by 11, may accumulate and rise suf-

ficiently to flow off in a small stream to the lower portion of the outlet 10, while the oil will flow off through the remaining upper portion of the outlet and the two liquids 5 may thus be received separated. The outer fixed electrode may be electrically connected to the ground, as at 12, and is also connected by a wire 13 to one of the high potential terminals of the current-regulating transformer T. The high potential transformer T is of the well known constant current type, comprising a fixed coil 16 and a vertically movable coil 17 adapted to move over a bundle of vertically disposed wires 18 and 10 connected to the walking beam lever 19, as by a flexible member 20. When the transformer T is set to produce a given maximum current, the current is automatically divided equally among the transformers, shown in 15 Fig. 3, or it is divided proportional to their respective needs, and under no circumstances will the current increase in value to an extent beyond that determined by the adjustment of the transformer. By this means 20 the separation of the oil from the water is sufficiently effected without danger of excessive current development.

I am convinced that the polarization of the water globules, so necessary for breaking 30 down the surface tension of the oil filaments inclosing the globules and permitting, on rupture, coalescence of the water particles, is effected by the difference of electric potential rather than the current that is made 35 to pass through the emulsion. Therefore, increase of current value is a disadvantage, tending to reduce the voltage as the current is enhanced and decreasing the polarizing effect as a result.

40 In my system the current remains substantially constant and the difference of potential is caused to vary as the changing exigencies of the process may demand.

Having described my invention, what I 45 claim is:—

1. Improvements in the art of separating liquids associated in emulsions which consists in providing a plurality of separators, each containing a pair of electrodes; connecting said electrodes in electric circuits to 50

produce an electrical field in each said separator through which the liquid is to be passed and automatically controlling the electric current by the condition of the liquid in said separators, to prevent its rise above a pre-determined value, but sufficient to produce the effect desired. 55

2. Improvements in the art of separating liquids associated in emulsions which consists in providing a plurality of separators, each containing a pair of electrodes; agitating the liquid in said separators; connecting the said electrodes in electric circuit to produce an electric field in each separator through which the liquid is to be passed and 60 automatically controlling the electric current by the condition of the liquid in said separators to prevent its rise above a pre-determined value but to maintain sufficient 65 strength to produce the result desired. 70

3. Improvements in the art of separating liquids associated in emulsions which consists in providing a plurality of separators each containing a pair of electrodes; passing emulsified liquid into the said separators; agitating the liquid while in the separators by its own movement or otherwise; connecting the said separators in parallel electric circuit; automatically dividing the electric current, of predetermined value, between 80 said separators and automatically controlling the electric current by the condition of the liquid in said separators, as a whole, to prevent its increase above a predetermined value, while maintained at sufficient strength 85 to produce the results desired. 90

4. Apparatus for separating liquids in emulsions comprising a series of vertical cylinders each containing a pair of electrodes and having an opening near its bottom and top end through which to pass liquids; a source of electric current; a regulator for said current to prevent its rise above a pre-determined value; and an electric circuit containing said regulator and said separators in parallel relation. 95

In testimony whereof I hereunto subscribe my name.

CHARLES W. McKIBBEN.
